CLAIM

I claim an ornamental design for a bicycle light housing, as shown and described.

DESCRIPTION

FIG. 1 is an upper front perspective view of the bicycle light housing;

FIG. 2 is a lower bottom perspective view of the bicycle light housing;

FIG. 3 is a rear lower side perspective view of the bicycle light housing;

FIG. 4 is a front elevational view of the bicycle light housing;

FIG. 5 is a rear elevational view of the bicycle light housing;

FIG. 6 is right side view of the bicycle light housing;

FIG. 7 is a left side view of the bicycle light housing;

FIG. 8 is a top plan view of the bicycle light housing of FIG. 1;

FIG. 9 is a bottom plan view of the bicycle light housing of FIG. 1; and,

FIG. 10 is a right side bottom perspective view of the bicycle light housing.

The broken-line disclosures, as shown through the openings in the housing, in FIG. 1 through FIG. 7 and FIG. 10, extending from the bottom surface, are understood to represent portions of the article in which the claimed design may be embodied, but which form no part of the claimed design.
